(75) Inventors: **Lee McDonald; Maurice Lavimodiere,**
both of Barrie (CA)

* cited by examiner

(73) Assignee: **Southmedic Incorporated,** Barrie (CA)

Primary Examiner—Ian Simmons
(74) Attorney, Agent, or Firm—Nikolai & Mersereau, P.A.

(**) Term: **14 Years**

(57) CLAIM

(21) Appl. No.: **29/141,424**

The ornamental design for an lightweight oxygen delivery system, as shown and described.

(22) Filed: **May 4, 2001**

DESCRIPTION

(51) LOC (7) Cl. **29-02**

FIG. 1 is a perspective view of the oxygen delivery system;
FIG. 2 is an elevation view from the rear.

(52) U.S. Cl. **D24/110; D24/110.1; D24/110.4;**
D14/206

FIG. 3 is an elevation view from the front.

(58) Field of Search **D24/110.4, 110.6,**
D24/164, 110.1, 110; D14/206, 205, 142;
128/200.28, 207.11, 204.18, 202.18, 205.25,
206.12, 206.21, 206.27

FIG. 4 is an elevation view from the side.

(56) References Cited

FIG. 5 is an elevation view from the other side.
